UNITED STATES PATENT OFFICE.

FRANK C. SIMMS, OF EAST PALESTINE, OHIO.

ELECTRIC HEATING UNIT.

Application filed May 29, 1925. Serial No. 33,585.

My invention relates to electric furnaces and particularly to heating units for resistance furnaces.

One object of my invention is to provide a combined muffle and resistor-supporting plate for an electric furnace.

Another object of my invention is to provide an enclosed heating unit for an electric resistance furnace, wherein the enclosing member constitutes a source of heat.

In practicing my invention I provide a combined muffle and resistor-supporting member, of a dense, hard material that is heat-and-electric-conducting, and that has a plurality of spaced, aligned tubular members of a ceramic electric-insulating material located therein to receive a resistor member. The tubular members have enlarged open ends to receive an alining and resistor-protecting member.

In the single sheet of drawings,

Figure 1 is a view, in vertical longitudinal section, of an electric furnace embodying my invention,

Fig. 2 is a view, in vertical lateral section, taken on the line II—II of Fig. 1,

Fig. 3 is a view, partially in side elevation and partially in longitudinal section, of a heating unit embodying my invention,

Fig. 4 is an end view thereof,

Fig. 5 is an end view of a modified form of heating unit embodying my invention,

Fig. 6 is an end view of another modification,

Fig. 7 is a view, in end elevation of another form of device embodying my invention,

Fig. 8 is a view, in side elevation, of a locking means,

Fig. 9 is a view, in section therethrough taken on the line IX—IX of Fig. 8,

Fig. 10 is a view, in side elevation, of a modified form of device embodying my invention, and,

Fig. 11 is a view, in end elevation, thereof.

An electric resistance furnace designated generally by the numeral 11 in Figs. 1 and 2 of the drawings, comprises a plurality of U-bricks or blocks 12 of a suitable refractory heat-insulating material, built up to constitute a plurality of walls enclosing a furnace chamber 13. While I have illustrated a furnace chamber that is substantially square in lateral section, I do not wish to be restricted thereto, as any desired size and shape of furnace chamber may be employed.

A heating means for the furnace comprises a plurality of plates 14, illustrated more particularly in Fig. 3 of the drawings, of substantially rectangular form in both lateral and longitudinal sections. Each member 14 consists of a mass of initially-moistened, comminuted, heat-and-electric-conducting material, such as carborundum, that has been tightly compressed into the desired shape and dimensions. A plurality of aligned tubular members 15, of ceramic electric-insulating material, are located within the member 14 and extend longitudinally thereof. The members 15 are provided, at each end thereof, with enlarged end portions 16 for a purpose to be hereinafter set forth in detail. I preferably make the tubular members 15 in one piece, in order that there may be no joints from one end thereof to the other. However, if the length of the member 14 and therefore of the tubular members 15, should become too large to permit of manufacturing the members 15 easily and economically, I may make them of two or even of three pieces located in aligned and abutting relation.

The member 14 is made in a mold which has provision for holding the tubular members in their proper operative positions during the molding operation. Any desired sequence of steps in the molding operation may be followed, the main object being to provide a dense, homogeneous plate of the desired shape and dimensions, of initially-moistened, comminuted carborundum that is tightly compressed, particularly so around the tubular members.

After drying out and being heated to a relatively high temperature, such plates are relatively hard and dense and still withstand considerable shock without breaking or cracking, the tubular members 15 aiding in strengthening the plate.

A resistor member is located within the tubular members 15 and extends therethrough, and comprises a relatively heavy and preformed rod, wire, or bar of a suitable resistance material, such as nichrome.

The wire or rod is bent to substantially U-form or to hairpin shape, as is more particularly shown in Fig. 1 of the drawings.

Thus each individual resistor portion is located in two adjacent tubular members, and adjacent ends of the resistor members at one end of the furnace may be connected by any suitable means, here shown as clamping bars 18.

105

110

The end portions of the upper and lower resistor members of hairpin form may be made longer, as indicated at 19 and 21 respectively in order that they may project

5 through one wall of the furnace structure to have suitable supply circuit conductors (not shown) connected thereto. Bushings 22 may be located in the furnace wall to insulate the end portions 19 and 21 from the furnace structure.

10 If it is desired to employ a number of the combined muffle and resistor-supporting members 14 in end-to-end relation, it is highly desirable that means be provided to 15 protect the resistor member at the joint between the two abutting members 14. I employ for this purpose a relatively short bushing 23, of a ceramic electric-insulating material, which fits into the enlarged end portions 16 of the tubular members 15. The bushings 23 serve not only to protect the resistor member against particles that might accumulate thereon during the operation of the furnace, but serve also as means to maintain the abutting ends of the members 14 in proper operative alignment relatively to each other. I prefer to employ the bushings 23 not only between abutting members 14, but also at the end portions thereof where-

20 by I obtain a creeping distance between the resistor member and the electric-conducting material of the muffle plate that is greater than the direct distance therebetween. This construction is shown at both ends of the heating units in Fig. 10 of the drawings. Any suitable or desired means may be employed for holding the members 14 in proper operative positions against one wall of the furnace, or in any other position in

40 which it is desired to locate them. When the plates are to be located adjacent to one of the walls of the furnace, I may provide recesses 24 at the top and at the bottom of the furnace chamber, as illustrated in Fig. 12, whereby the plates will be held securely

45 within the furnace chamber. An additional means for aiding in aligning the combined muffle plates and resistor supporting members is constituted by relatively small members 25 that are of lens shape, as is illustrated more particularly in Figs. 8 and 9 of the drawings. These mem-

50 bers may be made either of the same kind of material as the members 14 or as the tubes

55 15. Each corner of the members 14 is provided with a small recess 26 that is of such shape as to receive a portion of the member 25. When four members 14 are to be located in the positions shown in Fig. 1, it is only necessary to employ one of the

60 alining members 25 that operatively engages a corner of each of the four members.

Fig. 5 illustrates a modified form of construction of a resistor supporting member

oval shape in lateral section, are employed instead of the circular members 15. This permits of the use of ribbon instead of the hereinbefore described wire or rod.

Fig. 6 illustrates another modification in which a member 29 that is made in the same manner as the member 14, has located therein a plurality of tubular members 31 of oval shape in lateral section, the longer dimension thereof being alined with the plane of the member 29. This form of flattened tubular member permits of using a resistor ribbon instead of a bar or rod, and it is to be noted that the greater surface of the resistor member is alined with the surfaces of the member 29. Both forms of resistor supporting and muffle plate members, illustrated in Figs. 5 and 6 permit of translating a greater amount of electric energy into heat, than is the case in the form illustrated in Fig. 4. The tubular members may be located closer to one side of the plate than to the other, in order that the resistor members may be located closer to the chamber than to the wall of the furnace; the length of the heat path into the chamber being thereby shortened and the thermal resistance against the flow of heat into the furnace wall being somewhat increased.

When the form illustrated in Fig. 6 is employed, the distribution of the heat over the surface of the muffle plates is more uniform than is the case when the forms illustrated in Figs. 4 and 5 are employed. While this may ordinarily not be of importance, there may be occasions when it is desirable to have as uniform a temperature as possible over the entire surface of the plate, in which case the form illustrated in Fig. 6 is preferably employed.

The muffle plate embodying any invention is not restricted to a plane and rectangular form, but it may also be made in any other suitable or desired form, such as the arcuate form illustrated in Fig. 7. A member 32 is

65 there illustrated as being of arcuate form, in end elevation, and being otherwise of substantially rectangular contours. A plurality of tubular members 33, of ceramic, electric-insulating material, are located in alined and spaced relation within the member 32, and extend longitudinally thereof.

The member 32 is made of carborundum that is initially moistened and is compressed under great pressure and is then heated to a high temperature to dry out all moisture contained therein.

The form of muffle plate illustrated in Fig. 7 may be employed in vertical shaft furnaces in which case a plurality of the arcuate members 32 are located in abutting relation to constitute a muffle that is substantially circular in outline. The radius of

85 65 curvature of each of the muffle plates must wherein tubular members 27, of flattened or of course, be made such that a chamber of

- the desired diameter is obtained. Any desired number of muffle plates may be located in superposed relation, in order to provide a furnace chamber of the desired height.
- 5 The muffle plate 32 may also be employed in a horizontal shaft furnace to surround a furnace chamber of substantially circular shape and extending longitudinally. Recesses 26 are provided at each corner of the plates 27, 29, and 32 to receive alining members 25. The ends of the respective tubular members 28, 31, and 33 are provided with enlarged end portions, as was hereinbefore described in connection with the members 15. Co-operating resistor-protecting and alining members 23 or similar thereto are to be employed whenever two of the plates are located in abutting relation, and also at the outside ends of the plates.
- 10 Figs. 10 and 11 illustrate another modification wherein provision is made for locating a resistor member at the joint between two muffle plates. To this end I provide a substantially semi-circular groove in the edge faces and locate therein a tubular member for receiving a resistor. A plate 34 is built up in substantially the same manner and of the same kind of materials as was hereinbefore described for the plate 14. A plurality of tubular members 35 are located within the body of the plate and are of the same kind of material and construction as the tubular members 15. The edge faces thereof are provided with semi-circular grooves 36 and a tubular member 37 is located within the circular groove, formed when two of the members 34 are located with their edge faces in abutting relation, as shown in Fig. 11.
- 15 The tubular members 35 may be of the same general form as was hereinbefore described in connection with the members 15, that is they may be of one piece and have enlarged outer ends to receive an alining and protecting member 23. I may also make the members 35 shorter than the length of one block and have the abutting ends thereof located in a short tubular member 38.
- 20 The tubular members 37 and 38 are to be inserted between successive superposed plates 34 as they are located in their proper operative positions in the furnace structure. These tubular members will ensure a vertical alinement of the muffle plates, but I may provide additional means for maintaining the plates in alinement by a tongue and groove connection therebetween, as indicated by the numeral 39 in Fig. 11.
- 25 The plates 34 are alined longitudinally thereof by the members 23 inserted in the enlarged ends of the tubular members 37.
- 30 If tubular members 31, of oval section, are employed (similar to those shown in Fig. 6) and are located closer to one surface of the plate than to the other, the recesses 26 may be provided in the corners, in the same manner and for the same purpose as hereinbefore explained.
- 35 The device embodying my invention provides a form of combined muffle plate and resistor-supporting member that may be made of any desired thickness and also of any desired dimensions and contour. The carborundum employed in making the muffle plates is an excellent heat conductor, and as the tubular electric-insulating members located therein will not be subjected to any excessive strains the thickness of the walls thereof may be made relatively small, which will therefore reduce the resistance to the flow of heat therethrough to a minimum amount.
- 40 Wherever it is either desirable or necessary that the resistor member be covered, the use of the muffle plate embodying my invention is effective in protecting the resistor member while at the same time permitting of operating the resistor at relatively high temperatures without danger of unconfined distortion thereof which might otherwise cause either short circuits between adjacent portions of the resistor member, or grounds between the resistor and metal portions of the furnace structure. Where it is desirable to have a substantially uniform distribution of heat over the entire surface of the muffle plate, this may be effected by the use of the modification illustrated in Fig. 6 of the drawings. It is possible of course to locate the tubular members closer together than is shown, whereby the heat distribution over the surface of the plate will be substantially uniform. The resistor members located in the tubular members may operate at a relatively high temperature and the entire plate will reach a relatively high temperature that will be substantially uniform over the surface of the plate, which will, therefore, constitute a source of uniformly distributed heat.
- 45 While the heat generated in the individual resistor portions located in the tubular members will be substantially uniform laterally of the resistor members or in a direction of the thickness of the plate, the heat that is transmitted to the surface of the muffle plate located adjacent to a wall of the furnace is conducted to the other surface of the plate by reason of the fact that the highly compressed carborundum is an excellent conductor of heat. This prevents, to a great extent, any accumulation of heat on that side of the plate away from the furnace chamber.
- 50 The ceramic tubular members 15, 28, 31, and 32 will serve also as a means for strengthening the plate with which they are respectively associated. This will be especially true of the members 31, and a muffle plate embodying my invention is especially adapted to withstand hard usage in a fur-

nace incident to placing material in or removing it from the furnace chamber.

While I have illustrated certain specific embodiments of my invention, I do not desire to be limited thereto, but intend that any modifications coming within the scope of the appended claims shall be included thereunder.

I claim as my invention:

1. A combined muffle and resistor-support, comprising a plate of refractory, heat-and-electric-conducting material, and a tubular member, of electric-insulating material, in said plate for removably receiving a resistor member.
  2. A combined muffle and resistor-support, comprising a shaped plate of comminuted, initially-moistened, compressed, heat-and-electric-conducting refractory material, and a plurality of tubular members, of ceramic electric-insulating material, in said plate for removably receiving a resistor member.
  3. A combined muffle and resistor-support, comprising a plate of initially-moistened, compressed, comminuted carbórumundum, and a plurality of tubes of refractory electric-insulating material located in said plate for receiving a resistor member therein and for covering the same over substantially its entire length.
  4. In an electric furnace, in combination, a plurality of muffle and resistor-supporting members located in abutting relation, a plurality of spaced alined tubes of electric-insulating material located in each of said members, and means interfitting with the adjacent ends of said tubes for holding said muffle members in alinement.
  5. A combined muffle and resistor-support, comprising a hard, dense plate of initially-moistened, refractory, heat-and-electric-conducting material, and a plurality of tubular resistor-receiving members, of electric-insulating material, in said plate, each member embodying means for effecting a greater creeping distance between a resistor therein and the plate at the ends thereof, than the direct distance between said parts.
  6. In an electric furnace, in combination, a plurality of formed refractory resistor-supporting plates, of substantially rectangular form, located in abutting relation, and a single means interfitting with and extending into a corner portion only of the abutting plates for maintaining them in alinement.
  7. In an electric furnace, in combination, a plurality of formed refractory plates of a hard, dense, heat-and-electric-conducting material located in abutting end-to-end relation, a plurality of tubular members, of electric-insulating material having enlarged end portions, located in spaced and alined positions in said respective plates, and means interfitting with the adjacent enlarged end portions of said tubular members for maintaining said plates in alinement relatively to each other.
  8. A combined muffle and resistor support, comprising a hard, dense member of predetermined form and of heat-and-electric-conducting material, and a plurality of spaced, alined, tubular members, of ceramic electric-insulating material, located in said member for receiving and supporting a resistor member extending through said resistor support in the plane thereof.
  9. In an electric furnace, the combination with a plurality of walls enclosing a furnace chamber of predetermined form, of a combined muffle and resistor-supporting member therein conforming to a portion of one of said walls and supported adjacent thereto, said member comprising a plate of highly compressed, heat-and-electric-conducting material and a plurality of tubular members, of refractory electric-insulating material, extending longitudinally therethrough for receiving a resistor member.
  10. A combined muffle plate and resistor-support, comprising a removable plate of initially-communited, compressed heat-and-electric-conducting material, and electric-insulating means within said plate for receiving, supporting, and protecting a resistor member located therein and for strengthening said plate.
  11. A combined muffle plate and resistor-support, comprising a formed plate of heat-conducting material, and tubular, electric-insulating, means within said plate for strengthening the same, and for removably receiving a resistor member and for protecting the same over substantially its entire length.
  12. A combined muffle plate and resistor-support, comprising a formed plate of heat-conducting material, and tubular, electric-insulating, means within said plate for strengthening the same, and for removably receiving a resistor member and for protecting the same over substantially its entire length, said tubular means being located closer to one surface of the plate than to the other.
  13. In an electric furnace, in combination, a plurality of formed refractory plates of a dense, heat-and-electric-conducting material located with their edge faces in abutting relation, each edge face having a groove therein, and a tubular member, of refractory electric-insulating material, located in the grooves in the edge faces, for receiving a resistor member and for maintaining said plates in alinement.
- In testimony whereof, I have hereunto subscribed my name this 26th day of May, 1925.

FRANK C. SIMMS.
